UNITED STATES PATENT OFFICE.

GEORGE HARTMAN, OF CINCINNATI, OHIO, ASSIGNOR OF TWO-FIFTHS TO EDWARD WENNING,
OF CINCINNATI, OHIO.

PRINTING-PRESS.

No. 883,802.

Specification of Letters Patent.

Patented April 7, 1908.

Application filed July 7, 1906. Serial No. 325,067.

To all whom it may concern:

Be it known that I, GEORGE HARTMAN, a citizen of the United States of America, and resident of Cincinnati, county of Hamilton, 5 State of Ohio, have invented certain new and useful Improvements in Printing-Presses, of which the following is a specification.

The object of my invention is a printing press in which the inking apparatus of each 10 printing roll may be removed readily either for cleansing it or for replacing it with another inking apparatus.

Referring to the accompanying drawings, in which is illustrated a printing press involving 15 my invention, Figure 1 is a view partly in longitudinal section and partly in side elevation of the impression cylinder, printing rolls, and the removable frames carrying the inking apparatus. Fig. 2 is a plan view of 20 the parts shown in Fig. 1. Fig. 3 is a detail sectional view on line $y-y$ of Fig. 2. Fig. 4 is a sectional view on line $z-z$ of Fig. 3. Fig. 5 is a detail view upon an enlarged scale 25 of the crank shaft of the mechanism shown in Fig. 4. Fig. 6 is a sectional view on line $x-x$ of Fig. 2. Fig. 7 is a detail view partly in side elevation and in section of the removable frame of the inking apparatus. Fig. 8 is a detail view of the ink fountain driving 30 mechanism.

Referring to the parts: Impression cylinder, A, is mounted revolvably in standards a , of a frame-work, a' . Upon frame-work, a' , the frame, b^2 , which carries the printing 35 rolls and inking apparatus is mounted to slide on ways in frame, a' , so as to allow the printing rollers, B, of which four are illustrated, to be brought in and out of contact with the impression cylinder. Shaft, a^2 , of 40 the impression cylinder carries a gear, a^3 . Into gear, a^3 , mesh gear wheels, b , which are mounted upon the shafts, b' , of the printing rolls, B. Shafts, b' , are mounted in the side walls of a main movable frame, b^2 , which 45 may be moved by means of a shaft, b^3 , carrying a pinion, b^4 , which meshes with a rack, a^4 , upon the fixed frame, a' , so that the main movable frame, b^2 , may be moved toward and away from the impression cylinder to 50 carry the printing rolls, B, into contact therewith. Formed upon the inner faces of movable frame b^2 , are a series of horizontal ways, b^{13} , in which are mounted a series of secondary movable frames, C, which carry

the inking apparatus. These secondary 55 movable frames, C, are of similar construction so that only one of them need be described. They have feet, c , to fit into the ways, b^{13} , so that the frames, C, are readily removable from the ways, b^{13} . To adjust 60 the frames toward and away from the printing rolls, B, I have provided adjusting screws, c' , which engage lugs, b^5 , upon the frame, b^2 , and engage the ends of the movable frames, C, for the purpose of adjusting 65 them toward and away from the printing rolls. In each of the movable frames, C, are mounted ink vat, c^2 , two sets, c^3 , c^4 , of ink conveying rollers, and two sets of reciprocating and rotating ink distributing rollers, c^5 , 70 and c^6 . Between the sides of the ink vat, c^2 , an inking roll, c^7 , is mounted, against which bear a series of arms, c^8 , the pressure of which against the rolls, c^7 , may be regulated by adjusting screw, c^9 , to regulate the thickness of 75 the ink along the roller, c^7 . The ink is conveyed from roller, c^7 , to roller, c^8 , by a roller, c^{10} , mounted at opposite ends upon reciprocating arms, c^{10} .

I will now describe the means by which the 80 various motions thus far described of the inking rollers is conveyed to them from the shaft, b' , of the printing rolls.

Adjacent to pinion, b , upon shaft, b' , is a pinion, b^6 , which meshes into a pinion, c^{11} , as 85 shown in Fig. 7, which pinion is mounted upon a shaft journaled between the walls of the secondary frame, C. This pinion, c^{11} , conveys motion to a series of three pinions, c^{12} , mounted similarly in the secondary 90 frame, C, which series of pinions, c^{12} , convey the rotating motion to the shafts of the reciprocating and rotating rollers, c^5 and c^6 . The pinions, c^{20} , and c^{21} , upon the ends of the shaft, c^5 , and c^6 , which mesh with the pinions, c^{12} , are elongated as shown in Fig. 2, so 95 as to allow of a transverse reciprocation of said shafts. The reciprocation of the shaft, c^5 , c^6 , as well as the reciprocation of the arm, c^{10} , and rotation of the inking roller, c^7 , is obtained from a pinion, b^7 , upon the end of the shaft, b' , opposite that upon which the pinion, b^6 , is located. Pinion, b^7 , meshes into a pinion, d , which is mounted upon a stud shaft, 100 d' , in the side wall of the secondary movable frame, C. Pinion, d , meshes with the secondary pinion, d^2 , likewise mounted upon the wall of a movable frame, C, which in turn 105

meshes with a pinion upon the shaft, D, which is mounted at one end in the side wall of the movable frame, C, and near its opposite end in the bottom of said frame. Shaft, 5 D, carries a bevel pinion, d^3 , which meshes with a bevel pinion, d^4 , secured upon a longitudinally mounted crank-shaft, d^5 , which itself is journaled in boxes, d^6 , secured upon the bottom of the frame, C. The crank- 10 shaft, d^5 , has two U-curves d^7 , d^8 , which are connected by links, d^9 , d^{10} , as shown in Fig. 4 with reciprocating arms, d^{11} , d^{12} , one end of each of which is journaled in lugs on the bottom of the movable frame, C, and the opposite 15 ends of which are coupled to grooved sleeves, d^{20} , d^{21} , on the ends of the shafts, c^5 , c^6 .

It is seen that the reciprocation of the crank-shaft, d^5 , imparts a transverse reciprocation of short movement to the shafts, 20 c^5 , c^6 , in opposite directions to each other, so that the ink upon the rolls, c^3 , c^4 , is evenly distributed upon each section of said rolls.

Upon the end of the shaft, D, opposite the end upon which the bevel gear wheel, d^3 , is mounted, a pinion, d^{25} , is mounted which meshes with a pinion, d^{14} , which is mounted upon a shaft, d^{15} , journaled in the partition wall, c^{14} , of the frame C. To the pinion, d^{14} , a link, d^{16} , is pivoted on a crank pin, which link at the opposite end engages a stud on the arm, c^{10} , which stud projects through a slot, c^{15} , in the wall of the frame, C, as shown in Fig. 7. The shaft, d^{22} , of gear, d^{14} , carries at its opposite end an eccentric pin, d^{23} , to 35 which is pivoted a pawl, d^{24} , which engages a ratchet wheel, c^{17} , upon the shaft of roller, c^7 , so as to convey an intermittent rotation thereto.

When it is desired to remove any one of 40 the inking apparatus, or frames, C, of the various printing rolls, B, it is seen that they may be removed bodily. When thus removed it is seen that the inking apparatus is very readily cleaned, or if it be desired to 45 change the color of the ink imparted to any one of the printing rolls, that this may be done by simply removing the secondary frame, C, and inserting a new frame, carrying an ink apparatus with a different color of 50 ink, thus avoiding the delays heretofore occasioned by cleaning out an inking apparatus and placing a new color in it whenever it was desired to change the colors being printed.

What I claim is:

1. In a printing press the combination of 55 an impression cylinder, a main frame mounted upon ways, means for moving the main frame towards and away from the impression cylinder, a series of printing rolls journaled in the main frame mounted so as to 60 contact the impression cylinder when the main frame is brought adjacent thereto, horizontal ways in the main frame adjacent to each printing roll, a removable secondary frame mounted upon each of the ways in the 65 main frame, and inking rolls journaled in the secondary frames.

2. In a printing press the combination of 70 an impression cylinder, a main frame mounted adjacent to the impression cylinder, means 75 for moving the main frame toward and away from the impression cylinder, a series of printing rolls mounted in the main frame, pinions upon the printing rolls, secondary removable frames mounted in the main frame, 75 inking rolls whose shafts are mounted in the secondary frame and gear wheels mounted upon the shafts in the inking rolls and adapted to engage with the pinions upon the printing rolls.

3. In a printing press the combination of 80 an impression cylinder, a main frame mounted reciprocally upon ways to be brought toward and away from the impression cylinder, printing rolls mounted in the main frame, 85 secondary frames mounted removably in the main frame and inking apparatus mounted in the secondary frame.

4. In a printing press the combination of a 90 main frame, printing rolls mounted in the frame, pinions upon each end of the printing rolls, secondary frames mounted removably in the main frame, a set of inking rolls mounted in the secondary frame consisting of rotating rolls and of rotating and reciprocating ink distributing rolls, a crank for reciprocating the said reciprocating rolls mounted in the secondary frame and gear wheels mounted upon said inking rolls and adapted to mesh with the pinions upon the printing 95 rolls when the secondary frames are brought adjacent to the printing rolls.

GEORGE HARTMAN.
